US00D756740S

(12) **United States Design Patent**
Caglar

(10) **Patent No.:** **US D756,740 S**
(45) **Date of Patent:** **** May 24, 2016**

(54) **PNEUMATIC NAILER**

(71) Applicant: **STANLEY FASTENING SYSTEMS, L.P.**, East Greenwich, RI (US)

(72) Inventor: **Tolga Caglar**, Middletown, CT (US)

(73) Assignee: **Stanley Fastening Systems, L.P.**, East Greenwich, RI (US)

(**) Term: **14 Years**

(21) Appl. No.: **29/492,664**

(22) Filed: **Jun. 2, 2014**

(51) LOC (10) Cl. **08-03**

(52) U.S. Cl.

USPC **D8/68**

(58) **Field of Classification Search**

USPC .... D8/61-70; 173/2, 13, 46, 109, 110, 173/114, 170, 178, 198, 214, 217; 227/8, 227/113, 114, 120, 130, 136, 142; 408/20, 408/35, 58, 67, 117, 124, 125, 234, 241 R; 429/92; 318/139; 362/119

CPC B25C 1/001; B25C 1/04; B25C 1/06; B25C 1/041; B25C 1/047

(57) **CLAIM**

The ornamental design for a pneumatic nailer, as shown and described.

DESCRIPTION

FIG. 1 is a top and right-side perspective view of a pneumatic nailer showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines are included for the purpose of illustrating portions of the pneumatic nailer that form no part of the claimed design.

1 Claim, 7 Drawing Sheets
